UNITED STATES PATENT OFFICE.

WILLIAMSON D. ANDERSON, OF TUCSON, ARIZONA, AND EDWARD J. SHEARER, OF LORDSBURG, NEW MEXICO.

LOW-WATER ALARM.

1,127,156.

Specification of Letters Patent.

Patented Feb. 2, 1915.

Application filed September 3, 1914. Serial No. 860,068.

To all whom it may concern:

Be it known that we, WILLIAMSON D. ANDERSON, a citizen of the United States, residing at Tucson, in the county of Pima, State of Arizona, and EDWARD J. SHEARER, a citizen of the United States, residing at Lordsburg, in the county of Grant and State of New Mexico, have invented certain new and useful Improvements in Low-Water Alarms; and we do declare the following to be a full, clear, and exact description of the invention, such as will enable others skilled in the art to which it appertains to make and use the same.

15 Our invention relates to improvements in low water alarms for boilers and more particularly to those employing the expanding qualities of metal for the purpose of rocking a lever to sound an alarm.

20 The main object of the invention is to provide a device of this character which may be simply and inexpensively constructed and which will be highly efficient in operation.

In carrying out the above end, we provide a 25 horizontal elongated thermal member, longitudinal links pivotally connected to the opposite end portions of said member, a steam controlling valve, an upright lever pivoted to said links and stops on said lever and said 30 thermal member for preventing excessive movement of the former in a plane transverse to the latter.

A further object is to position the above 35 mentioned stops on the thermal member so as to allow a predetermined amount of expansion to take place in said member before the valve stem is operated.

With these and minor objects in view, the 40 invention resides in certain novel features of construction and combination herein described and claimed and shown in the drawings wherein:—

Figure 1 is a front elevation of our improved low water alarm, the thermal tube being contracted; Fig. 2 is a similar view showing the position of the various parts when the thermal tube is expanded; Fig. 3 is a vertical transverse section through the entire device, taken on the line 3—3 of Fig. 50 1; Fig. 4 is a horizontal section taken along the plane of the line 4—4 of Fig. 1; Fig. 5 is a vertical longitudinal section through the form of the device previously illustrated; Fig. 6 is a similar view showing a slightly

different form of construction; and Fig. 7 is a detail vertical section on line 7—7 of Fig. 5.

In the accompanying drawings, from Figs. 1 to 5, we have shown our improved low water alarm as comprising a horizontally disposed thermal tube 1 having its opposite ends threaded as indicated at 2 for the reception of polygonal caps 3 the latter having hollow pivot studs or bosses 4 extending laterally from two of their parallel sides, the bores of said studs receiving stop screws 5 by means of which a pair of links, to be described, are held against removal.

As most clearly seen in Fig. 5, the tube 1 is formed integrally with an upright water column 6, the same projecting a short distance below said tube and rising a considerable distance therefrom, the upper and lower ends of said column 6 receiving nipples 7 by means of which the column 6 may be connected to a boiler at such a point as to position the thermal tube 1 at or near the lower water level of the boiler. Formed integrally with the upper portion of the water column 6 and lying in the same plane with the thermal tube 1, is a lateral tubular extension 8, the outer end of which is closed by a screw plug 9 having an inwardly extending stop finger 10, the latter limiting the movement of a valve to be described. The upper side of the tubular extension 8 is provided with a steam inlet nipple 11 and an outlet nipple 12, the former being connected to the steam space in the boiler while the latter is connected to a suitable alarm 13, preferably a whistle. Formed in the tubular extension 8 and between the nipples 11 and 12, is a conical valve seat 14 which is normally closed by a conical valve 15, the latter having an operating stem 16, triangular in cross section or otherwise reduced between the valve 15 and the outlet nipple 12, passing across the bore of the water column 6 and having its free end passed slidably through a stuffing box 17 which is formed on the column 6 and in alignment with the extension 8. It will be seen that the extreme outer end of the stem 16 projects beyond the stuffing box in order that a set screw 18 carried by the upper end of a lever 19, may contact therewith for the purpose of actuating the same to unseat the valve 15. As seen in Fig. 7, the upper end of the lever 19

is split and provided with a clamping screw 19' whereby to retain the screw 18 in adjusted position.

The lever 19 may be of any suitable configuration but preferably has its lower end bifurcated to provide a pair of depending legs 20' which straddle the water column 6 and the thermal tube 1 at their point of intersection, said legs resting upon lugs 20' formed on the column 6 and having hollow pivot studs or bosses 21 projecting laterally therefrom and receiving pivot eyes 22 of pairs of operating links 23 and 23', the outer ends of said links being pivotally mounted upon the studs 4 beneath the heads of the screws 5 while their inner ends are held against dislocation by stop screws 25 threaded into the bores of the bosses 21.

As most clearly seen in the side elevations, the inner end of the links 23 are deflected downwardly or offset as indicated at 26, while the links 23' have their inner ends deflected upwardly as indicated at 27, thereby causing the pivot eyes 22 to be spaced vertically. It may here be explained however, that the links 23 and 23' would operate to equal advantage were they of rectilinear formation.

As clearly seen in Figs. 1 and 2, the upper portion of the lever 19 is provided with an inwardly projecting stop finger 28 which underlies the stuffing box 17 and is adapted to prevent upward movement of said lever.

Although, under favorable conditions, the proper expansion of the thermal tube 1 could be obtained without the provision of an insulating jacket, the opposite ends of said tube are preferably surrounded by jackets of this character which are spaced therefrom thus providing dead air spaces entirely surrounding said ends. The operation of this form of the device as well as the form now to be described, will be herein-after explained.

By reference to the drawings, it will be seen that the thermal tube and the water column are formed of a single casting in the form of the invention previously described. In some cases, however, it becomes expedient to form the tube in two sections indicated at 1' in Fig. 6 and to externally thread the inner ends of said sections as indicated at 1'', the latter being engaged with threaded bores or bosses 6'' near the lower end of the water column 6'. With this exception, the construction illustrated in Fig. 6 is identical with that illustrated in the first five figures of the drawings and a further description thereof is not thought to be necessary.

With the device as above described, its operation is as follows: The upper and lower ends of the water column 6 are connected respectively with the steam and water spaces of a boiler and the nipple 11

is connected with said steam space. As long as the water level within the boiler remains at a level above the thermal tube, the latter will be expanded only to a predetermined extent. When however, the water level within the boiler recedes to a point below the thermal tube, the steam from the boiler, the temperature of which is appreciably higher than that of the water, will enter the water column 6 and the thermal tube, therefore expanding the latter longitudinally to cause the links 23 and 23' to move outwardly; this outward movement rocking said lever and forcing the valve stem 16 inwardly thus opening the valve 17 to allow steam, coming into the nipple 11, to pass through the tubular extension 8 and to be discharged from the nipple 12 into the alarm 13 thereby sounding the latter. Excessive inward movement of the valve 15 will now be checked by the stop finger 10 as hereinbefore suggested.

Coming now more particularly to the illustration disclosed in Fig. 1: it will be seen that the inner ends of the links 23 and 23' are upheld by the lugs 20' when the thermal tube is contracted, the set screw 18 then receding from the valve stem 16 as seen in Fig. 1. It will therefore be seen that, before the valve stem 16 is moved inwardly, (the valve being held closed by steam pressure), expansion of the thermal tube will move the lever to the position seen in Fig. 2 while further expansion will rock the lever to open the valve.

It may here be explained that the expansion of the thermal tube, acting to cause the screw 18 to contact with the stem 16, is caused by the heat of the water from the boiler while the further expansion operating the valve 15, is caused by the temperature of steam entering said tube. It will therefore be seen that the action of the device is simultaneous with a drop in the water level.

We have described our invention with considerable minuteness but we do not wish to be limited to details other than those amplified in the appended claims.

Having thus described our invention, what we claim as new and desire to secure as Letters-Patent is:

1. A device of the character described comprising a thermal tube closed at its opposite ends and having an inlet opening, a pair of longitudinal links secured at their outer ends to the opposite end portions of the tube having their inner ends spaced vertically, and an upright lever having its lower end pivoted to said spaced ends of the links and an alarm to be operated by movement of the upper end of said lever.

2. A device of the character described comprising an elongated thermal member, a pair of longitudinal links secured at their

outer ends to the ends thereof having their inner ends spaced vertically, and an upright lever having its lower end pivoted to said spaced ends of the links and an alarm 5 to be operated by movement of the upper end of said lever.

3. A device of the character described comprising an elongated thermal member, a pair of longitudinal links secured at their 10 outer ends to the ends thereof and having their inner ends spaced horizontally; an upright lever having its lower end pivoted to said spaced ends of the links, a valve casing adjacent the upper end of the lever 15 and having an operating rod located in the path thereof and a stop on said lever for limiting its movement in a plane transverse to said member.

4. A device of the character described 20 comprising an elongated horizontal thermal member, a pair of substantially horizontal links pivoted to one side thereof near its ends, and having their inner ends lying in vertically spaced planes, a valve casing 25 spaced upwardly from said member and having a valve provided with an operating stem, an upright lever pivoted at its lower end to said spaced ends of the links and having its upper end located adjacent the 30 valve operating stem and a stop on said lever and adapted to underlie a portion of the casing to limit upward movement of said lever.

5. In a low water alarm for boilers, an 35 upright water column adapted to be connected at its upper and lower ends with the steam space and water space respectively within a boiler and having threaded apertures in its opposite sides at a point opposite the 40 lowest safety level of the water, a horizontal thermostatic tube made in sections and having its inner ends engaged with said apertures, caps closing the outer ends of said tube sections, a pair of links 45 connected at their outer extremities with said caps and having their inner extremities offset vertically and vertically spaced, and an upright lever pivotally connected to said offset extremities; combined with an alarm, 50 connections between the latter and the steam space of the boiler and a valve in said alarm connections actuated by the movements of said lever.

6. In a low water alarm for boilers, an 55 upright water column adapted to be connected at its upper and lower ends respectively with the steam space and water space of a boiler, and having apertures in its opposite sides at a point opposite the lowest 60 safety level of the water, a horizontal thermostatic tube made in sections whose inner ends engage said apertures, caps closing the outer ends of said tube sections, a pair of links connected at their outer extremities 65 with said caps and having their inner ex-

tremities vertically spaced and an upright lever pivotally connected to said vertically spaced extremities; combined with a whistle, a lateral extension on the water column and having a pair of nipples whereof one 70 is adapted to be connected with said whistle and the other with the steam space in the boiler, a valve within said extension, a stem passing through the column and located adjacent the free end of said lever and an adjustable contact member carried by said lever.

7. In a low water alarm for boilers, a horizontal thermal tube closed at its opposite ends, an upright water column having a portion rising from the thermal tube and a portion depending therefrom, said column having connections at its upper and lower ends designed to be connected respectively with the steam space and water space of a 80 boiler, a tube projecting laterally from the upper end of the water column, said tube having a steam inlet and steam outlet, a valve seat between said inlet and outlet, a valve in said seat and having a stem projecting beyond one end of the tube, an upright lever having its upper end located adjacent the outer end of said stem, the lower end of said lever being bifurcated and straddling the thermal tube, links pivoted at their 85 outer ends to the outer ends of the thermal tube and having their inner ends spaced vertically and pivoted to the bifurcated end of said lever, stop lugs on the lower end of said water column, and a stop finger on the upper 90 end of the lever.

8. In a low water alarm for boilers, a horizontal thermal tube, caps closing the opposite ends thereof and having laterally projecting pivoted bosses, an upright water 105 column having a portion rising from said thermal tube and a portion depending therefrom, said column having connections on its upper and lower ends designed to be connected respectively with the steam space 110 and hot water space of a boiler, a tubular extension projecting laterally from one side of the water column at its upper end, a stuffing box on the opposite side of said column, said extension having a steam inlet and steam outlet, a valve seat between said inlet and outlet, a valve in said seat and having a stem projecting through said stuffing box, an upright lever adjacent the side of the column on which the stuffing box is formed, 115 a set screw passing through the upper end of said lever and bearing against the outer end of said valve stem, a finger projecting inwardly from said upper end of the lever and underlying the stuffing box, the lower 120 end of said lever being bifurcated and straddling the thermal tube and water column at their point of intersection, links pivoted at their outer ends upon said pivot bosses and having their inner ends spaced vertically, 125 130

4
laterally projecting pivot bosses formed on the bifurcated end of said lever, to which the inner ends of said links are pivoted, and stop lugs formed on the lower end portion of the upright water column.

9. In a low water alarm for boilers, a horizontal thermal tube closed at its opposite ends, an upright water column rising from and communicating with the thermal tube, a connection at the upper end of said column to be connected with the steam space of a boiler, a similar connection communicating with the interior of the thermal tube and adapted to communicate with the water space of the boiler, a valve casing adjacent the upper end of the column, a valve in said casing and having an operating stem, an upright lever having a bifurcated lower end

straddling the thermal tube, the upper end of said lever contacting with said stem, and two pairs of substantially horizontal links pivoted at their outer ends to the ends of the thermal tube, their inner ends being spaced vertically and pivoted to the bifurcated end of the lever, one pair of said links being located on each side of said tube. 25

In testimony whereof we have hereunto set our hands in presence of two subscribing witnesses.
